SERGE USUN, OF SAO PAULO, BRAZIL

FILM CONTROLLING MECHANISM

Application filed July 20, 1928. Serial No. 264,288.

The object of this invention is to provide means whereby a film for a motion picture machine may be employed and properly timed after the perforations along one edge have become worn, resulting in the imperfect projection of the pictures.

A further object is to effect this result by the use of means for engaging that row of perforations opposite the one usually engaged, and which remains in good condition long after the openings forming the first row, or other row of perforations primarily engaged have become enlarged and fail to function properly.

15 A further object is to provide a Geneva stop arrangement in which the film is first caused to buckle slightly, is next moved forward, and then stretched slightly, and then stopped for the production of the picture.

20 With the foregoing and other objects in view, the invention consists in the novel construction and arrangement of elements described, illustrated and claimed, it being understood that modifications may be made 25 within the scope of the claims without departing from the spirit of the invention.

In the drawings forming part of this application,

Figure 1 is a view of the mechanism in side elevation, with a pressure device in section, at the left of the view.

Figure 2 is a section on line 2-2 of Figure 1.

Figure 3 is a section on line 3-3 of Figure 1.

Figure 4 shows, by the use of arrows, that slack is first produced in the film, then forward movement, then slight stretching, and thereafter the film is stationary long enough for producing the picture.

Figure 5 is a detail chiefly in section, in a plane indicated by line 5-5 of Figure 1, and shows especially a pair of idler wheels mounted on a shaft and adapted to hold the film with reference to one of the rollers referred to below.

Figure 6 is a detail in section showing the engagement of the perforated film by one of the rubber idler wheels or rollers.

50 The film 10 is engaged by upper notched

wheel 11 and passes between the latter and idle wheel 11', and passes thence over a roller 12 with which idlers 13 cooperate, this roller 12 having a friction surface, or having teeth 12' engaging the series of perforations on the 55 film opposite to the series engaged by the usual type of mechanism, or primarily engaged thereby.

Star wheel 14 moving with this roller 12 is engaged by the pin 16 on wheel 17, and 60 the latter is geared to wheel 18 carrying pin 19,—pin 16 being a little in advance of the other pin. The gearing includes meshing gear wheels 20, 21, 22, and the wheels 17 and 18 rotate in the same direction, or clockwise 65 in Figure 1.

Engagement is provided between pin 19 and star wheel 24, and idlers 24' cooperate with roller 25 moving with this star wheel. The film passes over roller 25 and is then 70 engaged by teeth on wheel 26 and by idlers 27, it being understood that any or all of the idlers may be of the double form shown in Figure 5.

Between rollers 12 and 25 the film passes 75 between pressure elements 30, 31, and Figure 4 shows that slight buckling movement is produced in the first stage of the operation, star wheel 14 being alone in effective operation,—then both star wheels and rollers 12, 80 25 are in effective operation in the second stage, and the film moves forwardly. In the third stage the upper star wheel has ceased to rotate, having been stopped in advance of the other, and the film is stretched slightly,—85 and in the fourth stage both star wheels are stationary and the film is also stationary, for the production of the picture. Cylinder 25 has a smooth or polished surface, and slight sliding movement takes place when the rotation of the upper cylinder 12 ceases, and the lower cylinder continues movement for a brief interval, as shown diagrammatically in Figure 4. Otherwise, there is sufficient 90 friction to carry the film along.

Having described the invention what is claimed is:—

1. In film controlling means, means including a Geneva stop mechanism for imparting positive intermittent movement to the film, 100

means including a second Geneva stop mechanism for imparting movement to the film, and gearing causing the rotation of the mechanism last named for an interval after the completion of operation of the mechanism first named, said mechanisms operating for equal periods of time, said stop mechanisms including star-wheel engaged pins each timed for engagement exclusively of the other in the first and third stages of movement of the film, and timed for simultaneous engagement during the intervening stage, producing slack in the film, uniform movement during the intervening stage, and then slight tensioning of the film.

2. In film controlling means, means including a Geneva stop mechanism for imparting positive intermittent movement to the film, means including a second Geneva stop mechanism for imparting movement to the film, means engaging the film at a point between said mechanisms, and gearing causing the rotation of the mechanism last named for an interval after the completion of operation of the mechanism first named, said mechanisms operating for equal periods of time, said stop mechanisms including star-wheel engaged pins each timed for engagement exclusively of the other in the first and third stages of movement of the film, and timed for simultaneous engagement during the intervening stage, producing slack in the film, uniform movement during the intervening stage, and then slight tensioning of the film.

35 In testimony whereof I affix my signature.
SERGE USON.
